UNITED STATES PATENT OFFICE.

SAMUEL V. WEEKS, OF CHATTANOOGA, TENNESSEE, ASSIGNOR OF ONE-HALF
TO ORLANDO F. JANES, OF CHATTANOOGA, TENNESSEE.

DISK PLOW.

SPECIFICATION forming part of Letters Patent No. 710,908, dated October 7, 1902.

Application filed October 23, 1901. Serial No. 79,722. (No model.)

To all whom it may concern:

Be it known that I, SAMUEL V. WEEKS, a citizen of the United States, residing at Chattanooga, in the county of Hamilton and State 5 of Tennessee, have invented a new and useful Disk Plow, of which the following is a specification.

This invention relates to disk plows of the combined riding and walking type.

10 The object of the invention is by the employment of adjustable and positively-operating mechanism to dispense with the employment of weights for imparting the requisite pressure on the furrow-opening disk, 15 thereby rendering the plow easier of operation and lessening the number of animals required to draw the same.

20 A further object is generally to simplify the construction, reduce the number of parts, and increase the efficiency of the plow.

25 With these and other objects in view, as will appear as the nature of the invention will be better understood, the same consists in the novel construction and combination of parts 25 of a disk plow, as will be hereinafter fully described and claimed.

30 In the accompanying drawings, forming a part of this specification, and in which like numerals of reference indicate corresponding parts, there is illustrated one form of embodiment of the invention capable of carrying the same into practical operation, it being understood that the elements therein exhibited may be varied or changed as to shape, proportion, 35 and exact manner of assemblage without departing from the scope of the invention, and in these drawings—

35 Figure 1 is a view in side elevation of a disk plow embodying this invention. Fig. 2 is a view in plan of the plow shown in Fig. 1. Fig. 3 is a view in plan, showing the disk plow of Fig. 1 converted into a double-disk plow. Fig. 4 is a sectional detail view showing the manner in which the permanent disk 45 is associated with its standard. Fig. 5 is a view in front elevation of the disk-holding plate. Fig. 6 is a fragmentary detail view of a portion of one of the disks.

40 Referring to the drawings, 1 designates the main frame-beam, the same having straight terminals 2 and 3 and an intermediate out-

ward bowed or bent portion 4, the latter being provided to permit operation of the permanent disk 5 without interfering with the said beam. The frame-beam has associated with it a land-side wheel 6, a front furrow-wheel 7, and a rear furrow-wheel 8, each of these wheels having a flanged or knife-edged tire or rim 9, as clearly shown in Fig. 2. The land-side wheel is vertically disposed, and the two furrow-wheels are inclined, as usual and as shown in the above-named figure. The shaft 10 of the land-side wheel is a crank and has one terminal bend formed to constitute an axle for the wheel, which latter is held thereon in the usual or any preferred manner, and the other terminal bend mounted in and projecting beyond a sleeve 11, carried by the lower end of the bracket 12, the upper end of which is bolted or otherwise secured to the terminal 70 3 of the frame-beam. Secured to or formed integral with the sleeve 11 is a semicircular rack-plate 13, the teeth of which are engaged by a latch carried by a lever 14, rigidly secured to the outer end of the crank-shaft terminal 15, as shown in Fig. 2, by which arrangement the shaft 10 may be rocked to lift or depress the land-side wheel as required and through the medium of the latch and rack-plate be firmly held in its adjusted position. 80

85 The front furrow-wheel 7 is mounted upon the crank-terminal 16 of a shaft 17, the upper portion of which is slidably secured in a sleeve or casting 18, having at one side orifice ears 19, which are engaged by an up-standing pin or stud 20 on an arm 21, the latter being firmly bolted to the terminal 3 of the frame-beam. The connection between the ears and the stud presents a joint or pivot upon which the casting 18 will turn, thus to 90 permits swinging of the furrow-wheel 7 to effect guiding of the plow to the right or left, as may be desired. The means for shifting the position of the furrow-wheel 7 consists of a clevis 22, pivoted to the outer end of a hitch-bar 23, the clevis being provided with plurality of openings to be engaged by the hook of the doubletree, by which means the depth of the cut of the disk 5 may be regulated through the medium of interposed mechanism, presently to be described, the pressure on the disk being progressively increased as 95 100

the hook of the doubletree is moved downward into engagement with the successive openings 24, and by this simple arrangement the employment of weights to increase the depth 5 of the cut of the disk is obviated. The clevis is provided intermediate of its ends, on its rear edge, with an orificed ear 25, with which engages one end of a rod 26, the other end of which engages a similar ear 27, carried by an 10 arm 28, projecting from the sleeve or casting 18. Through the medium of the rod 26 it will be seen that as side draft in either direction is transmitted to the clevis the front furrow-wheel is correspondingly turned, thereby 15 effecting guiding of the plow. The shaft 17, as shown in Fig. 2, is rectangular in cross-section, this arrangement being provided to prevent the shaft turning independently of the casting and also permit vertical adjustment 20 of the shaft, and with it the front furrow-wheel, when desired. To effect vertical adjustment of the shaft 17, a hand-lever 29 is provided, which is pivoted at its forward end to the outer side of the arm 28 and carries 25 any preferred form of latch mechanism to engage with the teeth of a segmental rack-plate 30, rigid with the arm 28. Connecting with the hand-lever 29 intermediate of its ends is a link 31, having its lower end secured to the 30 shaft 17 by bolt or rivet 32, the upper end portion of the link being provided with a plurality of openings 33, one of which is engaged by a bolt 34 to secure the same to the said lever. It will be seen by this arrangement of 35 mechanism that when the hand-lever is swung upward or downward the furrow-wheel 7 will be correspondingly elevated or depressed, whereby to permit the disk 5 to cut deep or shallow, as may be preferred. The plurality 40 of openings 33 is provided to permit adjustment of the link with relation to the lever 29, thereby to increase or diminish the range of adjustment of the front furrow-wheel.

Secured to the frame-beam is a yoke 35, 45 through which projects the hitch-bar 23, the yoke being provided with a transverse pin 36, against which the upper side of the said bar bears. From the yoke the hitch-bar curves upward and rearward and connects at its upper terminal with one end of a bar 37, pivoted for rocking movement upon the seat-standard 38, the lower end of the latter being rigidly secured to the terminal 2 of the frame-bar, as clearly shown in Fig. 2. The 50 rear end of the bar 37 curves downward and is provided with a plurality of openings 39 (shown in Fig. 1) to be engaged by one end of a link 40, the other end of which is pivotally connected with an ear 41, projecting 55 downward from the under side of the frame-beam. The seat-standard is provided with a plurality of openings 42, by which to permit adjustment of the bar 37 thereon, a bolt 43 serving to hold the bar 37 and seat-post 38 60 operatively connected. The connection between the hitch-bar 23 and the rocking bar 37 is through the medium of a bolt 44, adapted

to engage alined pairs of a plurality of openings 45 and 46, respectively in the upper ends of the said bars, by which arrangement 70 the requisite adjustment between all of the parts may be effected as the requirements of the case may demand.

The rear furrow-wheel 8 is journaled upon one crank-terminal of a shaft 47, the other crank-terminal of which is journaled in a sleeve or casting 48, carried by one side of the frame-beam. This furrow-wheel is adapted only for movement from right to left, and in order to hold it in line with the furrow 80 when the plow is moving forward a lug 49 is provided on the lower portion of the sleeve or casting to be engaged by the bend of the shaft 47 adjacent to the casting, as shown in Fig. 1, a stop-pin passed transversely through 85 the upper terminal of the said shaft and bearing upon the casting serving to hold the two parts assembled.

The disk 5, which is constructed and operates in the manner usual to implements of 90 this character, has disposed centrally of its back portion a plate 51, the back of which is provided with oppositely-alined recesses or depressions 52 to be engaged by projections 53 on one end of a sleeve 54, mounted in a 95 bearing 55, carried by the lower end of a hanger 56, the other end of the sleeve being provided with a head or flange 57 to bear against the bearing. The upper end of the hanger is rigidly assembled with the frame-beam by bolts 58, adapted to engage pairs of a plurality of openings 59 in the hanger, by which arrangement the hanger may be lowered to compensate for the wearing away of the disk. The disk 5 is provided at its center 100 with a cone-shaped opening 60, Figs. 4 and 6, provided with radial depressions 61 to be engaged by lugs or offsets 62, carried by the under side of the head of a screw 63, the screw passing through the sleeve and being 105 held associated therewith by a nut 64, screwed on its outer end and bearing against the flange 57. By the manner of associating the sleeve, plate, and disk these are all rigidly connected and are caused to rotate within the bearings 55. The coaction between the radial depressions 61 and lugs 62 of the screw-head serves to hold the screw against turning when the nut 64 is being seated, thus insuring the proper close union between the parts. 110

In Fig. 3 there is shown a form of embodiment of the invention wherein two disks are employed, and when this is desired a supplemental hitch-bar 65 is connected with the hitch-bar 23, to which is connected a supplemental rocking bar 66, operating in the same manner as the rocking bar 37 and connected with the frame through a link corresponding to the link 40 and operating in the same manner. The supplemental disk 66' is carried by 120 and associated with an angle frame-bar 67 in the same manner as the disk 5 is associated with its standard, the bend or angle 68 of the frame-bar 67 being bolted to the hitch-bar 23, 125 130

as clearly shown. The outer end of the supplemental hitch-bar 65 of course projects beyond the hitch-bar 23, and to this extended end the clevis 22 is pivoted, a rod 26 connecting the clevis with the ear 27, projecting from the sleeve or casting 18, as shown in Fig. 1. Of course when the supplemental disk is employed it will be necessary to remove the front furrow-wheel outward to one side in order to permit proper draft upon the machine, and to accomplish this result the arm 21 of the said furrow-wheel is elongated and provided with an angular offset 69, which is bolted, respectively, to the angular frame-bar 67 and 15 to the bracket 12 of the land-side wheel.

The seat-standard is herein shown as provided with a seat 70, which is employed where the plow is to be used as a riding implement; but should it be desired to convert the same 20 into a walking-plow handles 71 are to be attached to the seat-standard, as shown in dotted lines in Fig. 1.

From the foregoing description it will be seen that every element and adjustment requisite to the presentation of a thoroughly effective disk plow is provided and that by reason of the simplicity of the construction of the parts should one or more become broken or deranged they may readily be replaced. Furthermore, by the employment of the rocking hitch-bar and its connection with the rear portion of the frame-beam the desired downward pressure may be readily and quickly imparted to the disk or disks by simply detaching the 35 doubletree-hook from one opening in the clevis and moving it to another.

While not herein shown, it is to be understood that a suitable scraper may be employed in connection with the disk or disks to keep 40 the same free from any accumulation of soil.

Having thus fully described my invention, what I claim as new, and desire to secure by Letters Patent, is—

1. In a plow, a frame carrying a disk, and 45 means coacting with the rear portion of the frame and operated by change in the line of draft to vary the cut of the disk.

2. In a plow, a frame carrying a disk, a clevis, and connections between the clevis and 50 the rear portion of the frame, said connections operating upon change in line of the

draft on the clevis to vary the force of contact between the disk and the ground.

3. In a plow, a frame carrying a disk, a clevis, and rocking connections between the 55 clevis and the rear portion of the frame.

4. In a plow, a frame carrying a disk, a seat-standard on the frame, a rock-bar pivoted to the seat-standard and having one end connected with the rear portion of the frame, a 60 hitch-bar mounted for rocking movement on the frame, and having one end connected with the rock-bar, and a clevis carried by the other end of the hitch-bar.

5. In a plow, a frame carrying a disk, a 65 clevis, rocking connections between the clevis and the rear portion of the frame, and a furrow-wheel connected by interposed mechanism with the clevis.

6. In a plow, a frame-beam having straight 70 terminals and a bent or bowed intermediate portion, a hanger secured to the frame and supporting a disk having its rear face rotatable within the bowed portion of the frame, and supporting-wheels for the frame. 75

7. The combination with a frame carrying a permanent disk, of a frame-bar adapted for attachment to or detachment from the frame and carrying a supplemental disk, and means coacting with the rear portion of the frame 80 and operated by a change in the line of draft to vary the cut of the disks.

8. In a plow, a frame carrying a disk, a clevis, and connections between the clevis and the rear portion of the frame, a furrow-wheel connected by interposed mechanism with the frame, and an adjustable land-side 85 wheel connected with the frame.

9. In a plow the combination of a frame supporting a disk, a clevis, rocking connections between the clevis and the rear portion of the frame, a vertically-adjustable furrow-wheel, and connections between the furrow-wheel support and the clevis, substantially 90 as and for the purpose specified. 95

In testimony that I claim the foregoing as my own I have hereto affixed my signature in the presence of two witnesses.

SAMUEL V. WEEKS.
